UNITED STATES PATENT OFFICE.

WILLIAM BRASACK, OF OAK PARK, ILLINOIS.

CAR RETARDER.

Application filed April 28, 1922. Serial No. 557,150.

This invention relates generally to brakes and motion retarding devices and has particular reference to a car retarder. One of the objects of this invention is the provision 5 of a device of this character wherein the friction produced by the pull of the railroad car is always in direct proportion to the magnitude of this pull. In other words, a light or empty car on a slight grade will 10 cause only a slight pull and small friction on brake shoes, while a heavy loaded car on a steeper grade will produce correspondingly greater friction. There is no possibility of a run-away car, or excessive friction 15 for light loads.

Another object is to produce a brake eliminating the troublesome brake band which must necessarily be adjusted to meet the greatest possible load in order to avoid the 20 possibility of heavy cars overcoming the frictional power of the brake band, and which further requires frequent adjustment for wear.

Another object resides in the provision of 25 a spring near the attaching end of the cable which avoids transmitting the load directly to the ropes or the mechanism.

Figure 1 is a fragmentary side elevation of a car with the invention applied.

30 Figure 2 is a detached and fragmentary front elevation of the two swivel sheaves; and

Figure 3 is a detached detail and top plan view of the drum.

35 The car retarder as herein illustrated, consists of a drum (1) which is divided into two compartments by a central flange (2), each compartment being arranged for a rope which is attached to same. The arrangement 40 of the two ropes or cables is such that when one rope (3) is being wound upon the drum on one compartment, the other rope (4) unwinds and vice versa. The drum is mounted on a shaft (5) which is carried

45 by two swinging arms (6), the arms in turn being pivoted on the pin (7) carried by bracket (8). The bracket (8) is secured by bolts (9) to a post or any other suitable part of the building or separate structure. Two 50 brake wheels (10) are connected to the drum either by casting brake wheels and drum in one piece or attaching both independently to shaft (5). The bifurcated lever (11) is rigidly connected to the two swinging arms 55 and can be lifted by a rope (12) leading over swivel block (13) to hand lever (14). Hand

lever (14) is pivoted on pin (15) mounted on bracket (16) and is operated by a handle (17) attached to same. The hand lever mechanism can be attached by bolts (18) 60 or the like, to any suitable part of the building where control of the brake is desirable. A bracket (19) is attached by the bolts (20) to the same post which carries the drum and brake wheel mechanism. This bracket carries two brake shoes (21) made of any suitable friction material, and the two brake wheels (10) normally rest upon these brake shoes as shown on drawing.

The ropes (3 and 4) run over the two 70 swivel sheaves (22), which turn on pins (23), which are mounted in the swivel housings (24). The latter are attached by bolts to a common bracket (25) in such manner that the swivel sheaves may swing sidewise 75 a limited amount, but cannot fall over completely. The complete swivel sheave set is attached by bolts (26) to the post or other suitable support.

The free ends of the ropes (3 and 4) carry 80 a compression spring (27) and terminal coil chains (28) having an iron ball (29), attached at the end. One rope (4) is attached by the chain (28) to the railroad car (30) to be retarded, while the other rope (3) 85 lies free on the ground on the side of the track. The whole mechanism is preferably mounted on a post placed near the track on which the railroad cars are to be retarded.

The operation of my invention may in 90 one instance or application as illustrated, be described as follows: The preferable track grade for railroad cars is about 2½ percent which is of a slope to permit a railroad car to start and move by gravity. The railroad 95 car is attached by chain (28) to rope (4) the other end of which is wound on drum (1), as shown on drawing. The pull in the rope (4) produced by the railroad car tends to rotate the drum (1) in a clockwise direction, but inasmuch as drum (1) and brake wheels (10) are mounted on the same shaft (5) and are securely fastened together, the rope pull produces also a pressure on the 100 brake wheels which bear against their brake shoes (21) and thus create a frictional resistance which will counteract the tendency of the drum (1) to rotate and thereby retain the drum in a stationary position. If 105 it is desired to move or further drop the railroad car by gravity, the operator exerts a pull on handhold (17) which through lever 110

(14) and rope (12) will tend to lift lever (11) and shaft (5) thereby relieving the pressure of drums (10) on their brake shoes (21) so that drum (1) is now free to rotate which in turn will allow the railroad car to move ahead. While the rope (4) is being unwound by the moving railroad car the other rope (3) is being wound up, and when rope (4) is completely unwound and railroad car retarded to the end of its travel, the rope (3) will be completely wound up and ready to be attached to another car. The operation of the car retarder for rope (3) will be the same as for rope (4) except that the direction of rotation of drum (1) will be counter clockwise. The springs (27) interposed between the ropes (3 and 4) and the chains (28) will preserve the ropes and the whole mechanism from any sudden shocks. 20 The balls (29) will keep the chains (28) from detaching from the railroad car.

It will be noted that the pressures produced by the ropes (3 or 4) on shaft (5) are not the same, being larger for rope (3) than for rope (4). But owing to the fact that the hinge pin (7) is located on a higher elevation than shaft (5) and taking the difference in direction of rotation into account, the friction of brake wheels (10) on brake shoes (21) produced by these pressures will be practically the same.

I claim:

1. In a brake, a drum, a flexible member adapted to be wound on said drum, and means interposing frictional resistance induced by the pull on said member for retaining said drum against rotation, said means including a stationary brake shoe adapted to

support the entire weight of said drum during the braking operation of same. 40

2. In a brake, a drum, a flexible member adapted to be wound on said drum, a stationary brake shoe normally adapted to support the entire weight of said drum during the braking position thereof, and means for interposing frictional resistance between said drum and said shoe induced by the pull on said flexible member. 45

3. A brake as embodied in claim 2, and including means for lifting said drum from contact with said shoe to permit its free rotation. 50

4. In a brake, a two compartment drum, a pair of flexible members adapted for alternate winding on said drum compartments, a stationary brake shoe, a brake wheel connected to said drum and normally adapted to contact with said shoe, and means for bodily lifting said brake wheel and drum to release said drum from said stationary brake shoe 60 for free rotation.

5. In a brake, a two compartment drum, a pair of flexible members adapted for alternate winding on said drum compartments, a pair of brake wheels operatively connected with said drum, a pair of stationary brake shoes adapted for contact by said brake wheels, and means mounted eccentrically to the axis of said drum and brake wheels for lifting same to release said drum for free 70 rotation. 65

In witness whereof, I have hereunto subscribed my name, this 26th day of April, 1922.

WILLIAM BRASACK.
